UNITED STATES PATENT OFFICE.

CHESTER B. BROWN, OF MORRILL, NEBRASKA.

CULTIVATOR.

Application filed October 9, 1925. Serial No. 61,545.

This invention comprehends the provision of a motor operated cultivator or the like, designed to be used with any of the standard cultivating tools, and to accomplish the desired work more accurately and with a minimum of time and effort.

The nature and advantages of the invention will be better understood when the following detailed description is read in connection with the accompanying drawings, the invention residing in the construction, combination and arrangement of parts as claimed.

In the drawings forming part of this application, like numerals of reference indicate similar parts in the several views, and wherein:—

Figure 1 is a side elevation of the machine constructed in accordance with the present invention.

Figure 2 is a plan view of the running gear of the machine and showing how the auxiliary frame is supported by the main frame of the machine.

Figure 3 is a sectional view on line 3—3 of Figure 2.

Figure 4 is a fragmentary front elevation of the machine.

Figure 5 is a rear elevation.

Figure 6 is a detail view of the means employed for adjusting the auxiliary frame and showing one position of parts.

Figure 7 is a similar view showing another position of the parts.

Figure 8 is a fragmentary view partly in section showing the manner of bracing and supporting the frame of the machine from the front axle thereof.

Referring to the drawings in detail, A indicates generally the running gear of a motor operated vehicle, and wherein 10 represents the frame thereof. A motor of the Ford type is employed and indicated at 12, and this motor consequently includes a planetary transmission indicated at 13. Arranged directly behind this transmission and operatively connected with the drive shaft of the machine is a sliding transmission 14 including the control lever 15, which is employed for the reduction of speed as the occasion may require. At the front end of the machine the frame 10 is braced by members 16 arranged in divergent relation and adjacent the transverse end member of the main frame, as illustrated. The members 16 are connected with a bolt 17 passed through the

front axle 18 of the machine, and when it is desired to hold the body of the machine from movement with relation to the axle I employ side braces 19 adapted to be secured to the opposed sides of the frame 10, and designed to straddle and repose upon the front axle 18. The rear end of the frame 10 is braced by a transverse member 21 upon which the frame 10 reposes, the member 21 being connected with the spring perches 22 in place of the usual transverse spring, and arched as at 23 to pass over the differential.

Carried by and suspended from the main frame of the machine is an auxiliary frame clearly shown in Figures 1 and 2, and which auxiliary frame is rectangular in plan and of a size to project an appreciable distance beyond both sides of the machine, as shown. This auxiliary frame includes a front bar 24 arranged in advance of the front wheels of the machine and transversely thereof, and which bar is braced and supported by diagonally spaced bracing members 25 which have their corresponding rear extremities

70 suitably secured to the sides of the main frame, while their forward extremities are secured to the front bar 24 at the ends thereof. This front bar is further supported and braced by spaced parallel bracing members 26 which are suitably arched as shown in Figure 3 to pass over the front axle, the corresponding rear extremities of these members being secured to the rear or adjacent bar 27 of the auxiliary frame, while their 75 forward extremities are pivotally connected with the front bar 24. These members are also pivotally connected with the bar 27 as are also the spaced parallel members 28 of the frame, which have their forward extremities pivotally connected with the front bar 24. Again, the front bar 24 of the frame is braced and supported by spaced members 29 which are of angular contour to be secured to the sides of the main frame 10

80 from which they project forwardly and at an inclination to the front bar 24 with which they are secured. This construction and arrangement of parts not only supports the auxiliary frame upon the main frame of 85 the machine, but allows the auxiliary frame to be raised or lowered with relation to the ground to properly position the cultivator tools for the work to be accomplished, and also allows the auxiliary frame to be tilted endwise when the machine 90 is moving over inclined or hilly territory.

The rear bar 27 includes spaced upper and lower sections, as clearly shown in Figure 1, and between these sections are passed bolts 30 which are utilized to hold the cooperating parts 31 and 32, respectively, of a clamp associated with said bar, these clamps being used in conjunction with the shanks 33 of the cultivator tools indicated at 34. The shank 33 of each tool is provided with slots 34 so that the said tools are susceptible of vertical adjustment with relation to the adjacent bar 27 of the auxiliary frame, and also susceptible of tilting adjustment by reason of the slot and pin connection, indicated at 35. In addition to these adjustments of the cultivating tools the latter may be also slid along the bar 27 so as to space the tools any desired distance apart, and to accomplish this it is only necessary to loosen the bolts 30 to slide the latter between the sections of the transverse bar 27, as will be readily understood.

For the purpose of adjusting the auxiliary frame, I employ a shaft 36 journaled transversely of the frame 10 and having crank arms 37 and 38 at the ends thereof. The crank arm 37 is pivotally connected with the adjacent end of a link 39, while the lower end of this link is pivotally connected with a link 40 associated with the adjacent arch-shaped bracing member 26, as clearly shown in Figure 3. The other crank arm 38 is also connected with the adjacent arch-shaped bracing member 26, but indirectly so through a construction of means to be presently described, which allows the frame in its entirety to be raised and lowered with relation to the ground incident to the operation of the lever 41, and independently operated by means of a lever 42, when it is desired to only raise one end of the frame. This connecting means includes a frame 43 which is pivotally connected as at 44 with the crank arm 38. Pivotally mounted on this frame 43, as at 45, is the lever 42 above referred to, the lever 41 being carried by the shaft 36. A link 46 is pivotally connected with the lever 42 adjacent its lower end, and provides a connection between this lever and the adjacent arch-shaped bracing member 26 of the auxiliary frame. The frame 43 is provided with a rack bar 47 with which a pawl 48 cooperates to hold the lever 42 in a given position. The frame 43 is also formed with a sleeve 49 which slidably receives a guide rod 50, the lower end of the latter being connected with the same link 51 that provides a connection between the link 46 and the adjacent bracing member 26. It is by reason of this construction and arrangement of the rod 50 that the connecting means between the crank arm 38 and the auxiliary frame is afforded the proper rigidity to maintain the parts in working relation incident to the operation of either of the levers

41 and 42, respectively. When it is desired to raise and lower the auxiliary frame in its entirety from the front bar 24, the lever 41 is utilized, and when this lever is operated the frame 43 and its associated parts all move as a unit under the influence of the lever 41. However, when it is desired to raise or lower one end of the auxiliary frame independently of the other end thereof, the lever 42 is employed, which allows the frame 43 to be swung upon its pivotal connection 44 to so adjust the auxiliary frame independently of the lever 41, as will be readily understood. The levers 41 and 42 are arranged within convenient reach of the operator and can be very easily manipulated for the purposes intended.

While it is believed that from the foregoing description the nature and advantages of the invention will be readily apparent, I desire to have it understood that I do not limit myself to what is herein shown and described, and that such changes may be resorted to when desired as fall within the scope of what is claimed.

Having thus described the invention, what is claimed as new, is:—

1. In a machine of the character described, a wheeled frame, a transverse bar mounted rigidly on said frame, an auxiliary frame connected to said transverse bar to swing vertically thereon and also tilt endwise, said auxiliary frame including a transverse bar arranged parallel with the bar supported on the wheeled frame, end and intermediate bars, the latter being pivotally connected with the first mentioned transverse bar, diagonally disposed bracing members secured to the main frame and to the front transverse bar attached thereto, additional bracing members secured to the opposed sides of the main frame and including portions projecting forwardly and downwardly for connection with the said transverse bar, lever actuated means for raising and lowering the auxiliary frame, and lever actuated means for tilting one end of the auxiliary frame with relation to the other.

2. In a machine of the character described, a wheeled motor driven frame, a transverse bar mounted rigidly on the forward end of the frame, an auxiliary frame connected with the transverse bar and capable of being raised and lowered and also tilted endwise, said auxiliary frame including a rear bar, end and intermediate transverse bars which together with the rear bar are pivotally mounted on said transverse bar at the forward end of the main frame, lever actuated means for raising and lowering the auxiliary frame, and lever actuated means for tilting the frame endwise independently of the first mentioned means.

3. In a machine of the character described, a wheeled motor driven frame, a transverse

bar mounted rigidly on the forward end of said frame, an auxiliary frame suspended from said bar and capable of being raised and lowered and also tilted endwise, a crank shaft, a lever for operating said shaft, links connecting the crank portions of the shaft with the auxiliary frame, a plate pivotally connected with one crank portion of the shaft and interposed between the latter and the adjacent link, a second lever pivoted on said frame and pivotally connected with the adjacent link, rack teeth arranged on said plate, a pawl carried by the second men-

tioned lever and co-operating with said rack teeth, whereby said plate is moved in unison with the first mentioned lever to raise and lower the rear part of the auxiliary frame, and to allow the second mentioned lever to be used independently of the first mentioned lever to tilt one end of the frame, a sleeve carried by the plate, and a guide rod connected with the adjacent link and slidable through said sleeve for the purpose specified. ¹⁵

²⁰ In testimony whereof I affix my signature.

CHESTER B. BROWN.
